(57) **CLAIM**

The ornamental design for an audio player, as shown and described.

DESCRIPTION

FIG. 1 is a front, right and top perspective view of an audio player, showing my new design;

FIG. 2 is a front, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged detail view of the encircled region of FIG. 2.

The dashed broken lines in FIGS. 1-8 form no part of the claimed design and delineate portions of the audio player that form no part of the claimed design. The dot-dash broken lines in FIGS. 2 and 9 form no part of the claimed design and delineate the region of the audio player, including claimed subject matter, that is shown on an enlarged scale in FIG. 9.

1 Claim, 9 Drawing Sheets
